CLAIM

The ornamental design for a scissors sheath, as shown and described.

DESCRIPTION

FIG. 1 is a top front perspective view of a scissors sheath, showing my new design.

FIG. 2 is a bottom rear perspective view of the scissors sheath.

FIG. 3 is a front elevational view of the scissors sheath.

FIG. 4 is a rear elevational view of the scissors sheath.

FIG. 5 is a left side elevational view of the scissors sheath.

FIG. 6 is a right side elevational view of the scissors sheath.

FIG. 7 is a top plan view of the scissors sheath.

FIG. 8 is a bottom plan view of scissors sheath; and,

FIG. 9 is a top front perspective view of scissors sheath, shown with a pair of scissors illustrated in broken lines and inserted into the scissors sheath.

The broken lines in the figures show portions of the scissors sheath that form no part of the claimed design. The additional broken lines in FIG. 9 illustrating scissors show environment and form no part of the claimed design.

1 Claim, 8 Drawing Sheets
